UNITED STATES PATENT OFFICE

EMILE C. GUEDON, OF SCHENECTADY, NEW YORK, ASSIGNOR TO GENERAL ELECTRIC COMPANY, A CORPORATION OF NEW YORK

APPARATUS FOR PRODUCING SOUND

Application filed August 31, 1928. Serial No. 303,207.

My invention relates to apparatus for producing sound, and has for its principal object the provision of an improved sound producing apparatus which is capable of producing sound dependent on the contour of either the hill-and-dale groove type or the lateral groove type of sound record.

Various types of apparatus for the interconversion of sound and electrical impulses have been provided in the past. Many of these apparatus comprise a magnetic armature which is moved in a magnetic field either in accordance with electrical impulses dependent on sound or in accordance with the contour of a sound record. It is frequently desirable that such an apparatus be so mounted that it may be moved or rotated to one operating position for use with the hill-and-dale groove type of record and to another operating position for use with the lateral groove type of record. Due to the fact that the undulations of the hill-and-dale and lateral grooves are substantially at right angles, however, force is applied to the stylus either in the plane of armature movement or at right angles to this plane depending on the operating position of the apparatus.

When force is applied to the stylus in the plane of the armature movement, the armature does not move altogether in accordance with the contour of the record and the sound produced by the apparatus is likely to be distorted. In accordance with my invention, this difficulty is avoided by the provision of means for equalizing the force applied to the armature in its different operating positions.

My invention will be better understood from the following description when considered in connection with the accompanying drawings and its scope will be pointed out in the appended claims.

Referring to the drawings, Figs. 1 and 2 illustrate different operating positions of a sound producing apparatus wherein my invention has been embodied; and Figs. 3, 4 and 5 illustrate various details of the apparatus.

This apparatus includes a sound producing or magnetic pick-up device 1 which is mount-

ed on a support 2 so that it can be rotated either into the operating position illustrated by Fig. 1 for use with a lateral groove sound record or into the position illustrated by Fig. 2 for use with a hill-and-dale groove sound record. As indicated by Figs. 1 and 2, an ordinary steel needle is used in connection with the lateral groove record and a special diamond point stylus holder is used in connection with the hill-and-dale groove record.

As shown more clearly by Figs. 3 and 4, the sound producer or pick-up device 1 includes a magnet 3 provided with bifurcated pole pieces 4 and 5 between which an armature 6 is mounted. This armature is pivoted at 7, is surrounded at its central portion by an operating coil 8, is provided at its lower end with a recess and a stylus clamping screw 9 and has one of its ends in contact with a resilient block 10 whereby it tends to be maintained in its mid or neutral position.

The operation of the device is well understood by those skilled in the art and need not be described in detail. As the stylus follows the contour of the groove in the sound record, the upper or free end of the armature is moved to and fro between the upper projections of the pole pieces, thus reversing the flux in the coil 8 and producing therein a current dependent on the contour of the groove.

So long as the device 1 is in the operating position illustrated by Fig. 1, its weight is applied to the stylus in a plane at right angles to the motion of the armature 6 and does not tend to move the armature out of its central or neutral position.

When the device 1 is in the operating position illustrated by Fig. 2, however, its weight is applied to the stylus in a direction along the plane in which the armature moves and the armature no longer tends to return to its neutral position.

In the illustrated embodiment of the invention, this difficulty is avoided by the provision of a resilient member or spring 11 which is attached to the pole piece 5 at one of its ends, is provided with a prong-shaped projection at the other of its ends, and has an opening surrounding the lower end of the armature 6. In the operating position illus-

trated by Fig. 2, pressure for neutralizing the weight of the device 1 is applied by the spring 11 to the armature 6 through a projection 12 which is mounted on the side of the holder supporting the diamond point. 5 This projection fits into the bifurcated or prong-shaped projection in the end of the spring and in order that the spring may always exert the same equalizing pressure, the diamond point stylus holder is grooved at 10 the side as shown in Fig. 5, so that tightening of the screw 9 always causes it to be drawn tightly against the top, of the recess in the lower end of the armature. It will be readily understood that if the diamond point is 15 mounted on the projection 12, the necessity of rotating the device 1 is avoided.

In order to facilitate the placing of the stylus in contact with a sound record, it is 20 desirable that the stylus be easily seen. This result is achieved in the illustrated embodiment of my invention by cutting away the corners of the pole pieces so that the stylus protrudes from near the junction of converging sides of the device. 25

What I claim as new and desire to secure by Letters Patent of the United States, is:

1. In a sound producing device arranged to be moved into different operating positions, a movable armature arranged to be unaffected by the weight of said device in one of said positions and to be affected by said weight in another of said positions, and means for neutralizing the effect of said weight on said armature in said last mentioned position. 35

2. In a sound producing device arranged to be moved into different operating positions, a movable armature arranged to be unaffected by the weight of said device in one of said positions and to be affected by said weight in another of said positions, and a spring for neutralizing the effect of said weight on said armature in said last mentioned position. 45

3. In a sound producing device arranged to be moved into different operating positions, means for producing a magnetic field, an armature arranged to move in said field and 50 to be affected by the weight of said device in one of said positions, and resilient means attached to said magnetic means for neutralizing the effect of said weight on said armature.

4. In a sound producing device arranged to be moved into different operating positions, means for producing a magnetic field, an armature arranged to move in said field and to be affected by the weight of said device in one of said positions, resilient means attached to said magnetic means for neutralizing the effect of said weight on said armature, and means for predetermining the neutralizing force applied to said armature 65 through said resilient means. 130

5. In a sound producing device arranged to be moved into different operating positions, means for producing a magnetic field, an armature arranged to move in said field and to be affected by the weight of said device in one of said positions, a resilient member attached to said magnetic means at one of its ends, and means arranged to engage the other of its ends for applying to said armature a force whereby the effect of said weight on said armature is neutralized. 75

In witness whereof, I have hereunto set my hand this 30th day of August, 1928.

EMILE C. GUEDON.
